FIG. 1

FIG. 2

FIG. 1 is an isometric view showing the top, front, and left side of a restaurant, showing my new design; and FIG. 2 is an isometric view of the top, rear, and right side thereof.

The bottom will appear as a flat rectangle, relieved for entrances as indicated.

The dotted line showing of the lettering is for illustrative purposes only and forms no part of the claimed design.

I claim:

The ornamental design for a restaurant, as shown and described.
